UNITED STATES PATENT OFFICE

2,670,088

CUPOLA AND CHARGING APPARATUS
THEREFOR

John N. Richardson, Port Washington, Wis., assignor to Modern Equipment Company, Port Washington, Wis., a corporation of Wisconsin

Application June 30, 1950, Serial No. 171,330

12 Claims. (Cl. 214—36)

1

This invention relates to improvements in cupolas and charging apparatus therefor.

In the development of more efficiently operating cupolas, it has been found desirable to utilize the heat from the hot exhaust gases to preheat the fresh air which is blown into the bottom of the cupola. This heat is customarily discharged into the atmosphere and wasted. To accomplish this utilization, it is necessary to substantially seal the cupola and to withdraw the hot gases from the upper portion of the cupola through suitable ducts which direct said hot gases into economizers. The incoming fresh air is also directed into the economizers, and while passing therethrough is preheated by the absorption of heat from the hot exhaust gases. This regeneration of hot gases which would otherwise be wasted, effects a very marked saving of heat, and also brings about increased efficiency in the operation of the cupola.

It is apparent that in order to operate the cupola continuously under substantially sealed conditions, the charging must be done in a manner so as not to break the seal. Most of the sealed cupolas operate under pressures other than atmospheric, and breaking of the seal results in a disruption of the normal flow of gases as well as in fluctuations in the pressures within the cupola. Any such conditions must be avoided for proper cupola operation.

With the above in mind, it is the general object of the present invention to provide an improved cupola constructed to permit charging thereof while at the same time maintaining the integrity of its seal.

A further object of the invention is to provide an improved cupola construction of the class described, wherein a charging hopper is mounted on top of the cupola and has an open bottom in communication with the interior of the cupola, there being a bottom bell in said hopper for sealing off the communication between said hopper and the cupola, and there being normally open cover doors for the top of said hopper; said cover doors being movable to a closed position on said hopper, and said bell being movable downwardly during a cupola charging operation to permit a charge to drop into the cupola from the hopper, while said cover doors maintain the cupola in sealed condition.

A further object of the invention is to provide an improved cupola construction of the class described, wherein the hopper bell and the top wall of the cupola are water cooled, said bell having an elongated vertically extending stem for enclosing the water connections thereto.

2

A further object of the invention is to provide an improved construction of the class described, wherein power means is provided for opening and closing the hopper cover doors and for lowering and raising the hopper bell.

A further object of the invention is to provide an improved charging bucket for a cupola of the class described, said bucket so constructed that it is positionable close to and directly over the mouth of the charging hopper.

A further object of the invention is to provide an improved charging bucket of the two section type which insures proper distribution of a charge in the charging hopper.

A further object of the invention is to provide a charging bucket having a hollow central partition for accommodating the upwardly projecting stem of a charging hopper bell when the bucket is positioned over said charging hopper.

20 A further object of the invention is to provide an improved cupola construction and charging apparatus therefor which is strong and durable, efficient in operation, and otherwise well-adapted for the purposes described.

25 With the above and other objects in view, the invention consists of the improved cupola construction and charging apparatus therefor, and all of its parts and combinations, as set forth in the claims, and all equivalents thereof.

30 In the drawing accompanying and forming a part of this specification, wherein is shown one complete embodiment of the preferred form of the invention, and wherein like reference characters indicate the same parts in all of the views:

35 Fig. 1 is a view partly in vertical section and partly in side elevation of the improved cupola and the charging apparatus therefor;

40 Fig. 2 is a side elevational view of the improved cupola and charging bucket taken approximately along the line 2—2 of Fig. 1, parts being broken away and shown in section; and

45 Fig. 3 is a plan view of the improved cupola taken approximately along the line 3—3 of Fig. 2.

Referring to Fig. 1, the numeral 5 indicates the upper end portion of a cupola which may be cylindrical in shape and which may have the side walls thereof lined with refractory material 6. The upper end of the cupola is provided with a centrally apertured hollow top wall 7 which is water cooled and which is provided with suitable water connections 8. The cupola 5 is formed with an aperture 9 in the side wall thereof adjacent its upper end, and a duct 10 communicates with the aperture 9 to provide means through which the hot gases may be withdrawn from the cupola. The conduit 10 preferably leads to an

economizer (not shown) which utilizes the heat from the hot gases to preheat the fresh air entering the bottom of the cupola.

Suitably mounted on the top of the cupola is a charging hopper 11 having an open bottom positioned in and of substantially the same size as the central aperture in the top wall 7 of the cupola, as shown in Fig. 1. The hopper 11 may be of any suitable shape, the square cross sectional shape shown being merely illustrative. The open bottom of the hopper 11 is normally closed by a bell 12 of generally conical shape. The bell 12 is hollow and watertight, and projecting upwardly from the apex thereof is an elongated tubular stem 13. The interior of the stem 13 communicates at its lower end with the interior of the bell, and the upper end of said stem normally projects well above the upper margins of the hopper 11. Spaced a predetermined distance above the bell 12, a horizontal disc or cap 14 is positioned within the stem 13 and seals off the portion of the stem 13 therebelow. This forms an enclosed water chamber within the bell 12 and within the lower end portion of the stem 13. Above the disc 14 the stem 13 is formed with a longitudinal slot 15 which extends to the upper end of said stem, as shown.

An elongated water inlet pipe 16 extends vertically within the stem 13 from the upper end thereof downwardly through the cap 14 and into the bottom portion of the interior of the bell 12, as shown in Figs. 1 and 2. A water outlet pipe 17 has its lower end projecting a short distance below the cap 14 within the stem 13, and said pipe extends upwardly through the cap 14 to the upper end of the stem 13, as shown. At their upper ends the pipes 16 and 17 are connected respectively with pipes 18 and 19 which project laterally through the slot 15 of the stem 13 and may be connected to suitable water connections through flexible hoses (not shown).

A box shaped structural member 20 extends transversely of the hopper 11 adjacent the upper end thereof, as shown. The member 20 may be formed of a pair of channel members 21 and 22, said members being joined along their upper sides by a plate 23 of inverted V-shaped cross section. The plate 23 is apertured adjacent its midpoint, as at 24, and the flanges of the members 21 and 22 are cut away to permit the passage therethrough of the vertical stem 13. Depending from the structural member 20 and surrounding the stem 13 is a guide sleeve 25 which may be reinforced by the gussets 26.

Mounted on top of the cupola 5 adjacent the hopper 11 and in alignment with the structural member 20 thereof is an upstanding pulley supporting bracket 27 which carries at its upper end a rotatable pulley 28. Rotatably mounted within the structural member 20 is a rotatable pulley 29 which is positioned with a portion thereof extending through the slot 15 of the stem 13 and into the interior of said stem. An eye 30 is connected to the upper surface of the cap 14, and a chain 31 has one end connected to the eye 30. The chain 31 extends upwardly over the pulley 29 and laterally outwardly within the member 20 through an aperture 32 formed in the side wall of the hopper 11. The chain 31 extends over the pulley 28 and thence downwardly to the piston rod 33 of an hydraulic ram 34 which is mounted on the side of the cupola 5. Actuation of the ram 34 permits the stem 13 and the bell 12 to drop to the dot and dash line position thereof shown in Fig. 1, and said ram,

upon actuation in the opposite direction, is also operable to return said stem and bell to the solid line position thereof shown in the drawing.

A pair of cover doors 35 and 36 are hinged to opposite sides of the hopper 11 adjacent the upper margins thereof. The doors 35 and 36 are provided with ears 37 and 38 respectively to which are connected hydraulic rams 39 and 40 respectively which, in turn, are pivotally mounted on top of the cupola 5, as shown in Fig. 2. The rams 39 and 40 are operable to swing the doors 35 and 36 from their open positions shown, to closed positions wherein they substantially seal the open upper end of the hopper 11. The doors 35 and 36 are preferably notched out, as at 41 and 42, to permit the doors to close around the stem 13.

A charging bucket carriage track 43 is preferably positioned with its upper end terminating adjacent the upper end of the hopper 11, as shown in Fig. 1. Mounted for movement along the tracks 43 is a charging bucket carriage 44 having a pair of spaced charging bucket supporting arms 45 and 46 projecting from the forward end thereof. At their outer ends the arms 45 and 46 are provided with suitable bearings for the reception respectively of a pair of trunnions 47 and 48 which project laterally from a charging bucket 49 positioned therebetween.

The charging bucket 49 is preferably rectangular in shape, having spaced vertical side walls 50 and 51, and spaced vertical end walls 52 and 53. Extending transversely between the end walls 52 and 53 is a hollow vertical partition 54 which is preferably closed at its upper end and open at its bottom end. The partition 54 extends substantially the full height of the end walls 52 and 53, and said partition divides the bucket 49 into two separate sections. The side walls of the partition 54 are spaced apart a sufficient distance to readily accommodate the upper end of the hopper stem 13 therebetween, as shown in Fig. 2. The end walls 52 and 53 are cut away, as at 55 and 56, to permit the bucket 49 to move laterally into its position shown in Figs. 1 and 2 without interference from the upstanding stem 13. The hollow partition 54 may be provided with a horizontal plate 57 extending therein between the upper ends of the cut out portions 55 and 56.

The end walls 52 and 53 are formed with angled lower edges 58 which project upwardly and outwardly from adjacent the lower end of the partition 54. The lower edges of the side wall plates 50 and 51 are preferably horizontally extending, and they join the outer ends of the lower edges of the end wall plates at the bucket corners.

A pair of dump doors 59 and 60 are hinged to the end wall plates 52 and 53, as shown, and each of said dump doors, when in closed position, seals off the bottom of one of the sections of the bucket 49 formed by the partition 54. The pivots of the dump doors 59 and 60 are preferably so positioned with respect to the centers of gravity thereof, that when the bucket 49 is empty, said doors will swing to closed position. If the bucket is loaded, however, the load in the bucket will tend to swing the doors to open position to thereby discharge the load. The door 59 is provided with a pair of pivotally mounted latches 61 on opposite ends thereof, and the door 60 is provided with a pair of cooperating latch pins 62 fixed thereto and cooperable with the latches 61. When the doors 59 and 60 are swung to closed position, the

latches 61 drop into place over the latch pins 62, thereafter holding said doors in closed position.

A pair of projecting lugs 63 are formed on the end wall 52 of the bucket 49 above the latches 61, as shown in Figs. 1 and 2. Pivotaly mounted at the outer ends of the lugs 63 is a lever 64 having its lower end engageable with the underside of the adjacent latch 61. A lever 65, which is similar to the lever 64, is pivotally mounted within the hollow partition 54, as at 66, for movement in the same plane as that of the lever 64. The lower end of the lever 65 projects through an aperture 67 in the end wall 53 and is engageable with the underside of the adjacent latch 61, as shown in Fig. 1. A horizontal link 68 pivotally connects the upper end of the lever 65 to an upper end portion of the lever 64, said link extending through an aperture 69 in the end wall 52 as shown in Fig. 2.

A pair of lugs 70 project from the end wall 52 above the lug 63, and pivotally connected at its lower end to the lugs 70 is an upstanding trip lever 71, the upper end of which projects above the upper end of the bucket 49. A horizontal link 72 pivotally connects an intermediate portion of the lever 71 to the upper end of the lever 64 as shown.

Mounted on the upper end of each of the bucket carriage tracks 43 is a generally L-shaped bracket member 73 having its outer end projecting above and beyond the upper end of the tracks 43. Connected at one end to the outer end of one of the brackets 73, and connected at its opposite end to the outer end of the other bracket 73 is a chain 74. The chain 74 hangs in the path of the trip lever 71, and when the bucket carriage 44 moves the bucket 49 into the dumping position over the hopper 11, the trip lever 71 engages the chain 74 and is swung in a clockwise direction as viewed in Fig. 1. This pivots the levers 64 and 65 in the same direction and causes the lower ends of said levers to lift the latches 61. Lifting of the latches 61 frees the dump doors 59 and 60, and the load in the bucket 49 forces said dump doors outwardly to permit emptying of the bucket into the hopper 11. When the bucket is empty, the dump doors 59 and 60 swing back to closed position, and as the carriage 44 moves downwardly along the tracks 43 the trip lever 71 becomes disengaged from the chain 74, and the levers 64 and 65 move out of engagement with the latches 61 to permit said latches to drop into locking position on the pin 62.

In operation of the improved cupola charging device, the bell 12 and the stem 13 are normally in the position shown in Figs. 1 and 2, wherein the open bottom of the hopper 11 is sealed. The cupola 5 is in sealed condition, and the hot gases therefrom are withdrawn through the aperture 9 and the duct 10. The water cooled top wall 7 and the water cooling of the bell 12 and the lower portion of the stem 13 prevents excessive heating of the hopper 11 and the mechanism associated therewith.

When the doors 35 and 36 at the top of the hopper 11 are opened as shown in the drawings, the hopper 11 can be filled by the charging bucket 49. Due to the improved structure of the bucket 49 embodying the hollow partition, the stem 13 is accommodated to permit close positioning of the bucket 49 to the hopper mouth, and the bucket is divided into two separate sections whereby even distribution of the charge within the hopper 11 is obtained.

After the hopper 11 has been filled by the

bucket 49, the bucket 49 is lowered by the carriage 44 to the charging pit, and the rams 39 and 40 are actuated to swing the doors 35 and 36 inwardly to closed position. This seals off the top of the hopper 11. The ram 34 is then actuated to extend the rod 33 to the dot and dash line position shown in Fig. 1. This permits the bell 12 and the stem 13 to be lowered to the dot and dash line position shown in Fig. 1. As the stem 13 moves downwardly, the pulley 29 is accommodated within the slot 15 thereof. All of the charge in the hopper is thereby permitted to drop into the cupola, and as the charge drops into the cupola, it is deflected outwardly toward the periphery of the cupola by the conical upper surface of the bell 12.

During this operation the cupola is maintained in substantially sealed condition by the closed doors 35 and 36. When the hopper 11 is empty, the rod 33 of the ram 34 is retracted to thereby return the stem 13 and the bell 12 to their normal positions shown in solid lines in Figs. 1 and 2. The doors 35 and 36 are then swung to open position by retraction of the rams 39 and 40, and the hopper 11 is then ready to be refilled by the charging bucket 49.

It is apparent that the improved cupola charging device provides an efficient means for charging a sealed cupola from above without breaking the seal of the cupola. The improved hopper and charging bucket combination permits adequate water cooling as well as close positioning of the bucket to the hopper mouth, while at the same time insuring proper distribution of the charge in the hopper 11 when the charge is dropped from the two-section bucket.

Various changes and modifications may be made without departing from the spirit of the invention, and all of such changes are contemplated, as may come within the scope of the claims.

What I claim is:

1. In combination: a cupola having a water cooled top wall formed with a charging opening; a charging hopper having a bottom opening of substantially the same size as and in registration with said charging opening; a hollow structural member extending transversely across said hopper and having a vertical aperture extending therethrough; a hollow conical member normally positioned in and sealing said hopper bottom opening; an elongated tubular stem projecting upwardly from said conical member through the aperture in said transverse structural member; said stem extending a substantial distance above the upper end of said hopper; water connections for circulating cooling water through said hollow conical member; said water connections extending upwardly within said elongated stem; and actuating mechanism including a member extending within said hollow structural member and connected to said stem for moving said stem and conical member downwardly to open the hopper bottom opening whereby the contents of said hopper may fall into the cupola.

2. In combination: a cupola having a water cooled top wall formed with a charging opening; a charging hopper having a bottom opening of substantially the same size as and in registration with said charging opening; a hollow structural member extending transversely across said hopper and having a vertical aperture extending therethrough; a guide sleeve depending from said transverse structural member coaxially with said vertical aperture; a hollow conical member nor-

5 mally positioned in and sealing said hopper bottom opening; an elongated tubular stem projecting upwardly from said conical member through said guide sleeve and through the aperture in said transverse structural member, said stem extending a substantial distance above the upper end of said hopper; water connections for circulating cooling water through said hollow conical member, said water connections extending upwardly within said elongated stem; and actuating mechanism including a flexible member extending within said hollow structural member and connected to said stem for moving said stem and conical member downwardly to open the hopper bottom opening whereby the contents of said hopper may fall into the cupola.

3. In combination: a sealed cupola having a water cooled top wall formed with a charging opening; a charging hopper having a bottom opening of substantially the same size as and in registration with said charging opening; a hollow, structural member extending transversely across said hopper and having a vertical aperture extending therethrough; a hollow conical member normally positioned in and sealing said hopper bottom opening; an elongated tubular stem projecting upwardly from said conical member and communicating with the interior of said conical member, said stem projecting through the aperture in said transverse structural member and a substantial distance above the upper end of said hopper; a transverse cap positioned within said stem intermediate the length thereof and forming a water chamber within the portion of the stem therebelow and within said conical member; water connections for said water chamber extending through said cap and projecting upwardly within said elongated stem; actuating mechanism including a member extending within said hollow structural member and connected to said transverse cap for moving said stem and conical member downwardly to open the hopper bottom opening whereby the contents of said hopper may fall into the cupola.

4. In combination: a sealed cupola having a water cooled top wall formed with a charging opening; a charging hopper having a bottom opening of substantially the same size as and in registration with said charging opening; a hollow, structural member extending transversely across said hopper and having a vertical aperture extending therethrough; a guide sleeve depending from said transverse structural member coaxially with said vertical aperture; a hollow conical member normally positioned in and sealing said hopper bottom opening; an elongated tubular stem projecting upwardly from said conical member and communicating with the interior of said conical member, said stem projecting through said guide sleeve and through the aperture in said transverse structural member and a substantial distance above the upper end of said hopper; a transverse cap positioned within said stem intermediate the length thereof and forming a water chamber within the portion of the stem therebelow and within said conical member; water connections for said water chamber extending through said cap and projecting upwardly within said elongated stem; actuating mechanism including a flexible member extending within said hollow structural member and connected to said transverse cap for moving said stem and conical member downwardly to open the hopper bottom opening whereby the contents of said hopper may fall into the cupola.

5. In combination: a cupola having an opening at the top thereof; a charging hopper above said opening having a bottom opening in sealed communication with said cupola opening; a hollow structural member extending transversely across said hopper and having a vertical aperture therein; a vertically movably mounted closure member normally sealing said hopper bottom opening; a stem projecting upwardly from said closure member into the aperture of said hollow structural member; and actuating mechanism including a member extending within said hollow structural member and connected to said stem for moving said stem and closure member downwardly to open the hopper bottom opening, whereby the contents of said hopper may fall into the cupola.

6. In combination: a cupola having an opening at the top thereof; a charging hopper above said opening having a bottom opening in sealed communication with said cupola opening; a hollow structural member extending transversely across said hopper and having a vertical aperture therein; a guide sleeve depending from said transverse structural member coaxially with said vertical aperture; a vertically movably mounted closure member normally sealing said hopper bottom opening; a stem projecting upwardly from said closure member within said guide sleeve; and actuating mechanism including a member extending within said hollow structural member and connected to said stem for moving said stem and closure member downwardly to open the hopper bottom opening, whereby the contents of said hopper may fall into the cupola.

7. In combination: a cupola having an opening at the top thereof; a charging hopper above said opening having a bottom opening in sealed communication with said cupola opening; a hollow structural member extending transversely across said hopper and having a vertical aperture therein; a vertically movably mounted hollow closure member normally sealing said hopper bottom opening; a stem projecting upwardly from said closure member and communicating with the interior thereof, said stem extending into the aperture of said hollow structural member; a transverse cap sealed to said stem and forming a water chamber within the portion of the stem therebelow and within said hollow closure member; water connections for said water chamber extending through said cap; and actuating mechanism including a member extending within said hollow structural member and connected to said transverse cap for moving said stem and closure member downwardly to open the hopper bottom opening, whereby the contents of said hopper may fall into the cupola.

8. In combination: a cupola having an opening at the top thereof; a charging hopper above said opening having a bottom opening in sealed communication with said cupola opening; a hollow structural member extending transversely across said hopper and having a vertical aperture therein; a guide sleeve depending from said transverse structural member coaxially with said vertical aperture; a vertically movably mounted hollow closure member normally sealing said hopper bottom opening; a stem projecting upwardly from said closure member and communicating with the interior thereof, said stem extending within said guide sleeve; a transverse cap sealed to said stem and forming a water chamber within the portion of the stem therebelow and within said hollow closure member; water connections

for said water chamber extending through said cap; and actuating mechanism including a member extending within said hollow structural member and connected to said transverse cap for moving said stem and closure member downwardly to open the hopper bottom opening, whereby the contents of said hopper may fall into the cupola.

9. In combination: a cupola having an opening at the top thereof; a charging hopper above said opening having a bottom opening in sealed communication with said cupola opening; a hollow structural member extending transversely across said hopper and having a vertical aperture therein; a vertically movably mounted closure member normally sealing said hopper bottom opening; a stem projecting upwardly from said closure member into the aperture of said hollow structural member; a reversible power source; and a member extending within said hollow structural member and connected to said power source and to said stem for moving said stem and closure member downwardly upon actuation of said power source in one direction to permit the contents of said hopper to fall into the cupola.

10. In combination: a cupola having an opening at the top thereof; a charging hopper above said opening having a bottom opening in sealed communication with said cupola opening; a hollow structural member extending transversely across said hopper and having a vertical aperture therein; a vertically movably mounted closure member normally sealing said hopper bottom opening; a stem projecting upwardly from said closure member into the aperture of said hollow structural member; a fluid pressure operated ram; and a flexible connecting member extending within said hollow structural member and connecting said ram and stem for moving said stem and closure member downwardly upon actuation of said ram in one direction to open the hopper bottom opening and permit the contents of said hopper to fall into the cupola.

11. In combination: a cupola having an opening at the top thereof; a charging hopper above said opening having a bottom opening in sealed communication with said cupola opening; a hollow structural member extending transversely

across said hopper and having a vertical aperture therein; a vertically movably mounted closure member normally sealing said hopper bottom opening; a stem projecting upwardly from said closure member into the aperture of said hollow structural member; a fluid pressure operated ram mounted externally of said hopper; and a flexible connecting member having one end connected to said ram and having its other end extending into said hollow structural member and connected to said stem for moving said stem and closure member downwardly upon actuation of said ram in one direction to open the hopper bottom opening and permit the contents of said hopper to fall into the cupola.

15 12. In combination: a cupola having a top wall provided with a charging opening; a charging hopper having a bottom opening of substantially the same size as and in registration with said charging opening; a vertically movably mounted closure member normally positioned in and sealing said hopper bottom opening; a sheave rotatably mounted on the hopper above said closure member, a second sheave rotatably mounted laterally of said first sheave; an elongated flexible member connected at one end to said closure member and extending upwardly over said first sheave, then laterally over said second sheave and then downwardly; and hydraulically actuated means located below said second sheave externally of the hopper and connected to the other end of said flexible member for controlling movement of said closure member to open and close the bottom opening of the hopper.

JOHN N. RICHARDSON.
